AUTOMOBILE DOOR HINGE

Emil B. G. Lefevre, Detroit, Mich.

Application June 22, 1933, Serial No. 677,033

1 Claim. (Cl. 16—164)

This invention relates to hinges capable of general application but particularly designed for use on automobile doors. Automobile doors and bodies are frequently formed with substantially curved outer surfaces, and the edge of the door must clear the body when the door is opened. It is the general object of my invention to provide improved hinges for such purposes by which a door may be carried outward as it opens so that when the door is fully open the edge of the door will be substantially away from the outer surface of the body on which the door is mounted.

A further object of my invention is to provide a hinge which is effectively concealed when the door is shut.

To the attainment of this object, I provide a hinge comprising a pair of hinge plates connected by a pair of links which are pivotally connected together. Each link has one end pivoted to one of said plates and the other end guided for sliding movement relatively to the other plate.

My invention further relates to arrangements and combinations of parts which will be herein-after described and more particularly pointed out in the appended claims.

Preferred forms of my invention are shown in the drawings, in which

Fig. 1 is a side elevation of a portion of an automobile, broken away to show one of my improved hinges in operative position;

Fig. 2 is a detail view showing the door in open position;

Fig. 3 is an enlarged plan view of the hinge and associated parts, taken along the line 3—3 in Fig. 1;

Fig. 4 is a view similar to Fig. 3 but showing the hinge open;

Fig. 5 is a face view of the open hinge, taken along the irregular line 5—5 in Fig. 4;

Fig. 6 is a side elevation of one of the hinge plates, looking in the direction of the arrow 6 in Fig. 4;

Figs. 7 and 8 are perspective views of the hinge links;

Fig. 9 is a plan view of a slightly modified form of hinge;

Fig. 10 is a face view of the hinge shown in Fig. 9, taken along the line 10—10 in Fig. 9, and

Fig. 11 is a perspective view of one of the links used in the modified construction.

Referring to Fig. 1, I have shown a portion of an automobile body B having a pillar 10 on which a door D is hinged. I have shown the door as supported by upper and lower hinges indicated

generally by the letter H and identical in construction.

The details of construction of the first form of my improved hinge are shown in Figs. 4 to 8 inclusive. The complete hinge comprises a pair of hinge plates 12 which are identical in construction and which are adapted to be secured to the pillar 10 and door D by screws or bolts 14. Each hinge plate also comprises lugs 15 projecting at one side thereof and cam plates 16 at the top and bottom edges thereof, each cam plate being provided with a longitudinal slot 17.

A pair of hinge links 20 and 21 are provided, each having end bearing portions 22 and stubholding projections 23 at the opposite ends thereof. The link 20 is provided with spaced intermediate bearing portions 24 and the link 21 is provided with a single intermediate bearing portion 25.

When the parts are assembled, hinge pins 30 20 pivotally connect the link bearing portions 22 to the lugs 15 on the hinge plates 12, and a pin 32 extends through the intermediate bearing portions 24 and 25, thus pivotally connecting the links 20 and 21 to each other. Studs 33 are driven into recesses in the end projections 23 and project upward and downward therefrom into the cam slots 17.

When the parts are assembled as above described, each link 20 or 21 is directly pivoted to 30 the lugs 15 on one of the hinge plates 12 and has a sliding connection through the studs 33 and slots 17 to the other hinge plate 12. Also, the two hinge links 20 and 21 are pivotally connected together at their intermediate bearing points 24 35 and 25 by the pin 32.

The hinge is shown in its closed position in Fig. 3, and is inserted in associated depressions formed in the adjacent faces of the pillar 10 and door D, 40 best shown in Figs. 1 and 2. This is a matter of great advantage, as cutting away of the pillar 10 or the edge portion of the door D and the consequent weakening of these parts is thus effectively avoided.

As the door D is swung open, the cooperative action of the links swings the studs 30 apart, so that the moving hinge plate 12 is swung outward a substantial distance beyond the face of the body B, thus causing the edge of the door to clear the surface of the body, even when the body and door are substantially curved.

The links 20 and 21 are preferably provided with portions 40 which engage the surfaces of the lugs 15 when the door is opened and thus act 55

as stops, limiting outward movement of the door and rendering the use of the usual check straps unnecessary.

I have thus provided an extremely strong and rigid automobile door hinge well adapted to sustain the weight of a heavy door and to swing the door outward in such manner that the edges of the door and body are entirely clear of each other.

10 When the door is closed, the edges 50 (Fig. 4) move to the closely adjacent position shown in Fig. 3 and effectively conceal the hinges behind the surfaces of the pillar and door. These edges 50 may even overlap to form a windbreak without 15 interfering with the action of the hinges.

It will be further noted that this form of my improved hinge comprises only four parts, two of which are duplicates, and that all of the parts are well adapted for production by economical forging, press or casting operations.

20 Referring to Figs. 9 to 11, I have shown a slightly modified construction in which duplicate hinge plates 60 are connected by duplicate but reversed links 61. The hinge plates 60 are substantially identical with the plates 12 previously 25 described but the connecting links 61 are of somewhat modified construction.

Each link comprises a bearing portion 62 at one 30 end and a stud-holding projection 63 at the other end, together with an intermediate bearing portion 64. The parts 62 and 63 are offset in the same direction from the intermediate bearing portion, and the parts are so arranged and proportioned that the links may be assembled in reversed relation as clearly shown in Fig. 10, thus avoiding the use of two different types of connecting links.

Accordingly, the hinge shown in Figs. 9 to 11 is

constructed of a pair of duplicate plates and a pair of duplicate links only, thus requiring only two different parts to be manufactured or carried in stock.

This form of hinge differs slightly from that previously described in that the links are substantially straight and that the connecting portions directly engage the bearing portions without the provision of special abutments as in the form previously described. This form of hinge 5 also provides a slightly greater outward displacement of the door as the door is opened.

Having thus described my invention and the advantages thereof, I do not wish to be limited to the details herein disclosed, otherwise than as set forth in the claims, but what I claim is:—

A hinge comprising duplicate hinge plates each having spaced bearing lugs and offset upper and lower slotted flanges, a first connecting link pivoted at one end between the lugs of one of said hinge plates and having intermediate bearing portions spaced apart by a central opening in said link, a second connecting link pivoted at one end between the lugs of the other hinge plate and having a relatively narrow intermediate bearing portion extending through and positioned in said central opening and fitting closely between the spaced bearing portions of said first link, a pivot pin extending through and pivotally connecting said three intermediate bearing portions, each 20 connecting link having a free end portion nearly filling the space between the slotted flanges of the hinge plate to which said link is not pivoted, and means at both extremities of said free end portions extending into and freely slidable in the 25 slots in the associated offset flanges.

EMIL B. G. LEFEVRE.
